UNITED STATES PATENT OFFICE.

JACOB L. GORE, OF HUGO, OKLAHOMA, ASSIGNOR OF ONE-HALF TO ALMER L. BLOUN.
OF HUGO, OKLAHOMA.

AUTOMATIC TICKET-DISPENSING MACHINE.

1,337,837.

Specification of Letters Patent. Patented Apr. 20, 1920.

Application filed November 25, 1919. Serial No. 340,467.

To all whom it may concern:

Be it known that I, JACOB L. GORE, a citizen of the United States, residing at Hugo, in the county of Choctaw and State 5 of Oklahoma, have invented certain new and useful Improvements in Automatic Ticket-Dispensing Machines, of which the following is a specification.

Tickets of admission to amusements, public carriers and other purposes are usually provided in strips which are rolled for convenience of handling. These strips are turned from the roll and the tickets separated therefrom by being torn or cut. This 15 practice usually occupies one or both hands of the person dispensing the tickets and for this reason is undesirable.

The present invention enables the delivery of the tickets without occupying either 20 one of the hands of the operator, which are free to make change or for other purposes.

The drawings illustrate a preferred embodiment of the invention. However, it is to be understood that in adapting the same 25 to meet different conditions, various changes in the form, proportion and minor details of construction may be resorted to without departing from the nature of the invention as claimed hereinafter.

30 The drawings illustrate an embodiment of the invention, and on reference thereto,

Figure 1 is a side view of a ticket dispensing machine in elevation illustrative of the invention,

35 Fig. 2 is a front view of the machine, Fig. 3 is a section on the line 3—3 of Fig. 1 looking to the right as indicated by the arrow,

Fig. 4 is a top plan view,

40 Fig. 5 is a sectional detail on the line 5—5 of Fig. 2, looking to the right,

Fig. 6 is a sectional detail on the line 6—6 of Fig. 2, looking to the right,

45 Fig. 7 is a sectional detail on the line 7—7 of Fig. 6 looking to the left as indicated by the arrow.

Fig. 8 is a sectional detail on the line 8—8 of Fig. 7.

50 Corresponding and like parts are referred to in the following description and indi-

cated in the several views of the drawings by like reference characters.

The machine is essentially pedal operated thereby leaving both hands of the operator free. The frame work comprises a table 1 and an upright 2. The upright 2 is stayed by braces 3. A platform 4 is located some distance above the table 1 and is supported by the upright 2 and strengthened by braces 5. An incline 6 extends from the delivery 55 end of the platform 4 to the outer portion of the table 1 and acts in the dual capacity of a brace and a chute for delivering the tickets to the purchaser or recipient thereof. The operating mechanism is mounted upon the platform 4 and comprises a cutting mechanism, a feeder, a rotary stamp and an inker. The tickets are printed upon a strip 7 and such strip is wound upon a spool or drum 8, standards 9 rising from 60 the table 1 and formed with inclined notches 10 to receive the journals of the spool 8. In this manner the roll may be adjusted to any height according to its diameter. The portion of the strip 7 unwound from the 65 roll passes over the platform 4 and beneath a guide roller 12. As the strip is fed over the platform 4 it is stamped and cut so as to deliver the individual tickets.

The means for feeding the strip of tickets 80 over the platform 4 consists of a roller 13 which is preferably fixed to admit of engaging the strip to insure its positive feed over the platform. The feed roller 13 is mounted upon the upright 2 in advance thereof and 85 its surface is adapted to engage the strip 7 in a manner to insure its positive movement over the platform. The feed roller 13 is adapted to receive a counter clockwise movement, the latter being controlled 90 by a pedal mechanism. When the feed roller 13 is actuated, the ticket strip 7 is drawn from the roll and advanced over the platform 4. During the feeding of the ticket strip the cutting mechanism assumes 95 an operative position and when the pedal mechanism returns to normal position, the cutting mechanism will come into play and sever a ticket from the strip. The ticket thus severed will drop upon the incline 6 100

and move forward to a position to be received by the purchaser or other person intended to receive the same. A toothed wheel 14 is secured to one end of the feed roller 13 and a feed pawl 15 is in coöperation therewith.

The actuating member 16 is mounted in line with the axis of the feed roller 13, and a portion of its outer edge is toothed as indicated at 17. An arm 18 is secured to the actuating member 16 and pivotally supports the said pawl 15. A rack bar 19 coöperates with the toothed portion of the actuating member 16. The rack bar 19 is adapted to reciprocate vertically and is mounted in a guide way provided in the upright 2. An expansible helical spring 20 normally holds the rack bar 19 in elevated position and returns the same to normal position when the rack bar 19 is released, each being depressed by the pedal mechanism. When the rack bar 19 is depressed, the actuating member 16 is rotated in a counter clockwise direction and the feed pawl 15 engaging with the toothed wheel 14 of the feed roller 13 rotates the latter in the same direction thereby feeding a portion of the ticket strip to insure the severance of a ticket therefrom at the next operation of the cutting mechanism. When the rack bar 19 rises to normal position under the influence of the spring 20 the actuating member 16 is moved in a clockwise direction and the pawl 15 rides on the teeth of the element 14. The movement of the rack bar may be adjusted by means of a stop 21 which is adjustably connected to the upright 2 as indicated most clearly in Fig. 3. A stop 22 carried by the rack bar 19 is adapted to engage the stop 21 and thereby limit the downward movement of the rack bar. The upward movement of the rack bar is limited by a stop 23 which is adjustably connected to the rack bar. It will thus be seen that both the upward and the downward movements of the rack bar 19 may be adjusted. The pedal mechanism comprises a treadle 24 and a connecting rod 25 the latter being pivotally connected to the rack bar 19 and pedal as shown most clearly in Fig. 1. The treadle 24 may be conveniently rotated so as to be operated by the foot of the ticket dispenser.

When the tickets are to be dated or otherwise provided with matter to be stamped thereon such marking is effected by a stamp 26 which is of the rotary type and preferably disposed upon the rear side of the upright 2 and directly above the ticket strip. An inking roller 27 is in coöoperative relation with the rotary stamp 26 and supplies ink to the type. The stamp being of the rotary type is rotated by engagement of the type faces with the ticket strip 7.

The cutting mechanism is located at the outer or delivery end of the platform 4 and

comprises a fixed blade 28 and a movable blade 29. The fixed blade 28 is embedded in the platform 4. The movable blade 29 is pivoted at one end as indicated at 30 and its opposite end is upturned as indicated at 31. A tappet arm 32 adjustably connected with the actuating member 16 is adapted to engage the upturned end 31 of the pivoted blade 29 and actuate the same. A contractile helical spring 33 connected with the blade 29 returns the same to normal position preliminary to cutting the next ticket from the strip. The free end of the pivoted blade 29 operates in a guide 34. A guard 35 is disposed to prevent injury to the hand.

The operation of the machine may be briefly stated as follows:—The ticket strip in the form of a roll is mounted upon the standards 9 and an end portion is drawn from the roll and passed beneath the guide roller 12 and over the platform 4, and is adjusted so that when the pedal 24 is depressed, the feed roller 13 will operate to advance a portion of the strip corresponding with the ticket to be cut therefrom. As the ticket strip is drawn from the roll, the date or other data to be printed thereon is applied by means of the stamp 26. As the pedal 24 is depressed the actuating member 16 is rotating in a counter clockwise direction and the movable cutter member 29 assumes an operative position under the influence of the spring 33. When the pedal 24 is relieved of pressure the rack bar 19 is moved upward under the influence of the spring 20 and causes the actuating member 16 to rotate in a clockwise direction thereby bringing the tappet arm 32 in contact with the movable cutter member 29 which is depressed thereby severing the ticket from the strip. The feed of the ticket strip may be regulated by proper adjustment of the stops 21 and 23 and the cutting mechanism may be timed to operate properly by adjustment of the tappet arm 32 which is adjustably connected in any manner with the actuating member 16.

Having thus fully described my invention what I claim as new and desire to secure by Letters Patent, is:—

1. In an automatic ticket dispensing mechanism, an upright, a rack bar mounted in the upright, a pedal mechanism for imparting a vertical reciprocating movement to the rack bar, a feed roller, an actuating member adapted to have an oscillatory movement imparted thereto by means of the rack bar, and a feed pawl carried by the actuating member and adapted to intermittently operate the said roller.

2. In an automatic ticket dispensing mechanism, an upright, a rack bar mounted in the upright, a pedal mechanism for imparting a vertical reciprocating movement to the

rack bar, a feed roller, an actuating member adapted to have an oscillatory movement imparted thereto by means of the rack bar, a pedal mechanism for imparting movement to the rack bar, means for adjusting the movement of the rack bar in each direction, and a feed pawl carried by said actuating member and in coöperative relation with

the said roller to impart intermittent movement thereto.

10

In testimony whereof I affix my signature in presence of two witnesses.

JACOB L. GORE.
